[57] CLAIM

The ornamental design for a vacuum cleaner, as shown and described.

DESCRIPTION

FIG. 1 is a perspective view of a vacuum cleaner, showing our new design.

FIG. 2 is a front elevational view thereof;

FIG. 3 shows a right side elevational view thereof;

FIG. 4 shows a top plan view thereof;

FIG. 5 shows a bottom plan view thereof;

FIG. 6 shows a rear elevational view thereof;

FIG. 7 shows a left side elevational view thereof;

FIG. 8 shows a perspective view thereof, with the stick handle removed;

FIG. 9 shows a front elevational view thereof, with the stick handle removed;

FIG. 10 shows a right side elevational view thereof, with the stick handle removed;

FIG. 11 shows a top plan view thereof, with the stick handle removed;

FIG. 12 shows a rear elevational view thereof, with the stick handle removed; and,

FIG. 13 shows a left side elevational view thereof, with the stick handle removed.

FIGS. 1-7 show the claimed design in use as an upright vacuum cleaner and FIGS. 8-13 show the claimed design in use as a hand held vacuum cleaner. The broken lines are shown for environmental purposes only and form no part of the claimed design.
